CARRIAGE BODY

Alban M. Boudreau, Gardner, Mass., assignor to
Hedstrom Union Company, Fitchburg, Mass.

Filed Mar. 6, 1963, Ser. No. 73,850

Term of patent 7 years

(Cl. D14—14)

FIG. 1

FIG. 2

FIG. 3

FIG. 1 is a side view in perspective of a carriage body embodying my new design;

FIG. 2 is an end view thereof;

FIG. 3 is a top view thereof.

The dominant features of my design reside in the portions shown in full lines, with the broken line portions being omitted from FIGS. 2 and 3 for convenience of illustration. The side not shown is a mirror image of the side shown.

I claim:

The ornamental design for a carriage body, substantially as shown and described.
